Primary Examiner — Lilyana Bekic*(74) Attorney, Agent, or Firm* — Dorsey & Whitney LLP(57) **CLAIM**

We claim the ornamental design for an oral irrigator tip with bristles, as shown and described.

DESCRIPTION

FIG. 1 is a perspective view of an oral irrigator tip with bristles showing our new design.

FIG. 2 is a left side elevation view thereof.

FIG. 3 is a front elevation view thereof.

FIG. 4 is a rear elevation view thereof; and,

FIG. 5 is an enlarged, representative, fragmentary, cross-sectional view thereof taken along line 5-5 in FIG. 3.

The broken line showing of the oral irrigator in FIG. 1 illustrates environment and forms no part of the claimed design. All other broken lines illustrate portions of the oral irrigator tip with bristles that form no part of the claimed design.
